UNITED STATES PATENT OFFICE

90,990

DESIGN FOR A COOKING UTENSIL

Joseph M. Liebig, Peoria, Ill., assignor to Clarence J. White, Peoria, Ill.

Application June 24, 1933. Serial No. 48,526

Term of patent 7 years

To all whom it may concern:

Be it known that I, JOSEPH M. LIEBIG, a citizen of the United States, residing at Peoria, in the county of Peoria and State of Illinois, have invented a new, original, and ornamental Design for a Cooking Utensil, of which the following is a specification, reference being had to the accompanying drawing forming part thereof.

I claim:

The ornamental design for a cooking utensil, as shown.

JOSEPH M. LIEBIG.
